UNITED STATES PATENT OFFICE.

ALFRED ROBERTS SHARPLES, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

METHOD OF AND APPARATUS FOR ARRESTING ELECTRIC CURRENTS.

1,133,671.

Specification of Letters Patent.

Patented Mar. 30, 1915.

Application filed June 7, 1912. Serial No. 702,156.

To all whom it may concern:

Be it known that I, ALFRED ROBERTS SHARPLES, a citizen of the United States, residing in the city of Philadelphia, county 5 of Philadelphia, and State of Pennsylvania, have invented a Method of and Apparatus for Arresting Electric Currents, of which the following is a specification.

My invention is a method and apparatus wherein a non-conducting fluid is utilized to prevent a normal voltage current from following a discharge of abnormally high voltage current, for use primarily as a lightning arrester.

15 I have found that when certain non-conducting liquids are supplied by capillary attraction, in the form of a thin film, by the absorption of a proper medium, or by other suitable means so that it is disseminated or 20 mechanically held in the path of a current discharge between electrodes forming a spark gap or gaps, the usual flow of normal current across such gap or gaps, following the high potential discharge, is prevented.

25 While various liquids may be used, such as sulfur chlorid, amyl bromid, carbon bisulfid, bromoform (tribromomethane), chloroform (trichloromethane), and nitro-benzin (oil murbane), carbon tetrachlorid has 30 been found most satisfactory within the scope of my investigations, particularly for suppressing the spark and preventing ionization where the voltages are high.

Various electrodes, of bismuth, copper, 35 iron and other materials, have been found to produce satisfactory results when arranged to form a spark gap above the liquid, with the electrodes dipping into the liquid or removed from the body of the liquid and a 40 non-conducting absorbent material used for carrying the desired supply into the path of the current across the gap. I have found that the desired results are obtained efficiently and satisfactorily by means of electrodes of carbonaceous material having their 45 lower parts immersed in carbon tetrachlorid and their upper parts forming a spark gap above the liquid.

In the preferred form of my invention, 50 carbon plates, having their lower portions separated by a mica plate or other insulating material so that their upper portions form a spark gap, and tetrachlorid of carbon are sealed in a non-conducting con-

tainer, with the bottoms of the plates immersed in the liquid, whereby a supply of such liquid creeps or is fed upwardly into or in proximity to the spark gap. These plates are held together by suitable clamping means and arranged in series with non-inductive resistance.

It is my understanding that the liquid disseminated in the region of the spark gap is vaporized by the spark and there is thus absorbed a large amount of heat, whereby 65 the temperature is lowered below that which will support an arc. The gases liberated by volatilizing the liquid or vapor probably combine with particles in the arc to suppress the current which would otherwise be sustained by such particles.

In the accompanying drawings, Figure 1 is an end elevation of a current arresting apparatus or lightning arrester embodying my invention; Fig. 2 is a sectional view of 75 the same taken on the line 2-2 of Fig. 1; Fig. 3 is an elevation showing the face of a plate electrode comprised in my invention; Fig. 4 is an elevation showing an end of the plate electrode; Fig. 5 is a vertical 80 section taken transversely through the center of a group of plate electrodes and insulating separators; Fig. 6 is an elevation showing the construction of a modified form of plate electrode; Fig. 7 is a vertical section 85 taken transversely through the center of the plate shown in Fig. 6; Fig. 8 is a vertical section taken transversely through the electrodes of a modified form of the apparatus; Fig. 9 is a vertical section taken 90 transversely through the electrodes of a further modified form of the apparatus; and Fig. 10 is a sectional view of a still further form of the apparatus.

The apparatus, as illustrated in Figs. 1 95 and 2, comprises a container 1 having a cover 1^a which is hermetically sealed thereon and seals carbon tetrachlorid therein, the container having the internal bearings 1^b and 1^c integrally formed therewith. A 100 screw 2 connects the binding post 3, exterior to the container, with the resilient conducting member 4 which is fixed within the container on the bearing 1^b, the binding post being connected by a conductor 5 to 105 ground. A screw 6 fixes a resilient conducting member 7 within the container on the bearing 1^c. This conducting member is elec-

trically connected with the conducting holder 8 of a non-inductive resistance 9 which is disposed within the container and has its conducting holder 10 connected by the screw 11 with the binding post 12 exterior to the container; this post being connected by the conductor 13 with the line wire 14. The angular members 4 and 7, having the downwardly extending legs 4^a and 7^a, form a clamp for the carbon plate-electrodes 15 and 15' which are separated by the mica or other non-conducting plates 16, the several plates resting on the bottom of the container and being held in the desired relation by the clamp. The bottoms of the several plates are immersed in the carbon tetrachlorid or other liquid in the container and the tops of the plates 15 and 15' above the plates 16 are wholly separated to form the spark gaps 17 above the surface of the liquid. The plates 15 and 15' have beveled edges 15^a and the plates 15' have the channels 15^b, to avoid any tendency of current to discharge around the mica plates' edges contiguous to such beveled edges and channels and to prevent carbon deposits upon the mica.

The plate electrode 15', as illustrated in Figs. 3 and 4, has all its edges 15^a beveled and is provided with an angular channel 15^b, the legs of which extend upwardly from the sides of the plate, and the separators are provided with angular tops indicated by the dotted line 16^a. Such channels 15^b may be formed in both faces of plates 15' intermediate of plates 15', as illustrated in Fig. 5, the registering channels having the upper edges 16^a of the separators 16 between them. I may also provide the plate electrodes with an irregular, roughened or checkered surface above the channels 15^b, as by the grooves 15^c shown in Figs. 6 and 7. When the line 14 receives current of abnormally high potential, a discharge takes place by way of the conductor 13, post 12, screw 11, holder 10, resistance 9, holder 8, conductor 7, electrodes 15 and 15' above plates 16 and across gaps 17, conductor 4, screw 2, post 3 and conductor 5 to ground. This discharge having been effected the flow of normal current, which ordinarily follows a spark across a gap, is effectually cut off.

While the foregoing construction is the preferred embodiment of my invention, with the information that I have thus far obtained, I have secured satisfactory results with a number of constructions, type of which are illustrated in Figs. 8, 9 and 10.

The construction shown in Fig. 8 comprises a container 21; a base 22 of insulating material supported within the container; a pair of posts 23 supported by the base; conducting clamp screws 24 movable through the tops of the posts; corrugated metal electrodes 25 engaged by the screws,

and an electrode 25' between the electrodes 25; sheets of punctured asbestos, paper or cloth 26 disposed between the electrodes and extending into the tetrachlorid or carbon in the container; a conductor 27 containing the non-inductive resistance 28 and connecting a screw 24 with the line 29, and a conductor 30 connecting the other screw 24 with the ground. Here the absorbent properties of the insulating material 26 carries the carbon tetrachlorid into the field of the spark.

The construction shown in Fig. 9 comprises a container 31, an insulating base 32 therein, a pair of phosphor bronze springs 33 fixed to the insulation by the screws 34, a pair of plates 35 (provided with ribs 35') against which the springs press, a sheet of punctured asbestos 36 against which the electrodes are pressed by the springs, the conductor 37 containing the resistance 38 and connecting a screw 34 with the line 39 and the conductor 40 connecting the other screw 34 to ground. The absorbent material extends into carbon tetrachlorid and feeds the same into the field of the spark.

The construction shown in Fig. 10 comprises a vessel 41 containing carbon tetrachlorid, a pair of carbon electrodes 42 dipping into the carbon tetrachlorid, a glass separator 43 between the lower parts of the electrodes, the screws 44 which are threaded in suitable bearings 45 in the sides of the container and press the plates 42 against the glass separator, the conductor 46 which connects a screw 44 with the line 47 and a conductor 48 which connects the other screw 44 to ground. The separating means may be provided by glass rods considerably larger in diameter than the distance across the spark gap, thereby securing ample insulating resistance and a large surface of discharge.

It will be understood that the features of construction may be variously modified. The containers may be made of insulating material or metal (as iron) in combination with means for insulating the conductors. Electrodes of appreciable resistance may be used with consequent modification or elimination of separate resistance in circuit.

Having described my invention, I claim:

1. The method of arresting the flow of an electric current following a high potential discharge across a gap which consists in feeding a limited amount of a non-conducting fluid to said gap and destroying the arc by its vaporization of said fluid.

2. In a current arresting apparatus, the combination of a container, a non-conducting liquid therein, and means comprising carbon electrodes whereby a spark gap is formed above the surface of said liquid and said liquid is fed to said spark gap.

3. In a current arresting apparatus, the

combination of a container, a body of carbon tetrachlorid in said container, and means for forming a spark gap and feeding a limited amount of said carbon tetrachlorid to said spark gap.

4. In a current arresting apparatus, the combination of a container, a body of non-conducting liquid in said container and means comprising porous electrodes for forming a spark gap above said body and feeding liquid from said body to said spark gap.

5. In a current arresting apparatus, the combination of a container, a body of non-conducting liquid containing a halogen element in said container, said liquid being capable of eliminating a spark and means providing a pair of electrodes forming a spark gap above the surface of said body and for feeding said liquid to said gap.

6. In a current arresting apparatus, the combination of a container, a body of non-conducting liquid in said container and carbonaceous electrodes partially submerged in said body and forming a spark gap above the same, substantially as described.

7. In a current arresting apparatus, the combination of a container, a body of non-conducting liquid in said container, and means for forming a spark gap and feeding a limited amount of said liquid to said gap, said means comprising an electrode having an indented surface, substantially as described.

8. In a current arresting apparatus, the combination of a container, a body of non-conducting liquid in said container, plate electrodes partially immersed in said liquid and forming a spark gap, and an insulating separator between said plates, substantially as described.

9. In a current arresting apparatus, the combination of a container, a body of non-conducting liquid in said container, plate electrodes partially immersed in said liquid and forming a spark gap, one of said electrodes having a channeled face, and an insulating plate separator between said electrodes, substantially as described.

10. In a current arresting apparatus, the combination of a container, a body of non-conducting liquid in said container, plate electrodes partially immersed in said liquid and forming a spark gap above said body, one of said electrodes having a channel in a face thereof above said body, and an insulating plate separating said electrodes below said channel, said insulating plate having an upper edge registering with said channel, substantially as described.

11. In a current arresting apparatus, the combination of a container, a body of non-conducting liquid in said container, carbonaceous plate electrodes partially immersed in said container and forming a spark gap above said body, one or more of said plates being cut away along an edge or edges thereof, and a mica plate separating said electrodes below said spark gap, substantially as described.

12. In a current arresting apparatus, the combination of a container, a non-conducting liquid (adapted for suppressing an arc) in said container, electrodes in said container, said electrodes forming a spark gap, an insulating separator between said electrodes, and resilient conducting and clamping means whereby said electrodes and separators are pressed together.

13. In a current arresting apparatus, the combination of a container having bearings therein, a non-conducting liquid therein, carbonaceous plate electrodes in said container with their bottoms immersed in said liquid and their tops forming a spark gap, a mica separating plate between said electrodes, a pair of resilient contacts connected with said bearings whereby said electrodes and plates are pressed together, and a non-inductive resistance in said container electrically connected with one of said contacts.

In witness whereof I have hereunto set my name May, 1912, in the presence of the subscribing witnesses.

ALFRED ROBERTS SHARPLES.
